UNITED STATES PATENT OFFICE

GEORGE D. SHAEFFER, OF BUCYRUS, OHIO, ASSIGNOR TO W. A. RIDDELL COMPANY, OF BUCYRUS, OHIO, A CORPORATION OF OHIO

ROAD GRADER

Application filed November 14, 1929. Serial No. 407,102.

This invention relates, as indicated, to road graders and the like, and has specific reference to an attachment for such graders with which results heretofore not obtainable are rendered possible.

In the construction of macadam, asphalt, and similar types of roads, it is common to find a dirt or like soft shoulder extending longitudinally of the macadam or asphalt, which soft shoulder, however, is inadequate to properly sustain the macadam or asphalt. It becomes necessary, therefore, to remove the material occurring adjacent the body of road material and substitute therefor a concrete shoulder. This concrete shoulder then serves as a suitable lateral support for the asphalt or macadam and may also be utilized to effect a widening of the improved road surface. The removal of the shoulder which is to be replaced by the concrete shoulder has been accomplished in the past more or less by hand operation. The hand operation for so removing the shoulder is inexpedient in that the cost is excessive and the time required for doing the work is necessarily much longer than it is possible to spend in so improving the road. A grader carrying the common form of scraper blade is inadequate to accomplish the above outlined shoulder-removing operation in that the end of the grader blade is not adaptable to take a substantial cut from the solid shoulder.

My invention provides a means whereby the above outlined shoulder-removing operation which normally is effected by hand can be accomplished in a single operation; that is, a single passage of the grader along the road, and also effect a finished surface to the work not possible with the hand operation.

It is an object of my invention to provide a means whereby the above desirable ends can be expeditiously accomplished. Further objects of the invention will appear as the description proceeds. To the accomplishment of the foregoing and related ends, said invention, then, consists of the means herein-after fully described and particularly pointed out in the claims.

The annexed drawings and the following

description set forth in detail certain mechanism embodying the invention, such disclosed means constituting, however, but one of various mechanical forms in which the principle of the invention may be used.

In said annexed drawings:

Fig. 1 is a fragmentary part section, part side elevation of a grader embodying the principles of my invention; Fig. 2 is a plan view of the auxiliary implement-carrying frame; and Fig. 3 is a fragmentary elevation of the frame shown in Fig. 2.

Referring more specifically to the drawings and more especially to Fig. 1, the grader here illustrated is of the type wherein the main implement-carrying frame 1 is supported adjacent its rear end by means of brackets 2, which depend therefrom and are mounted on trunnions 3 which are carried by the crawler tread frame 4 of the common type crawler tractor 5. The rearward end of the frame 1 is connected with the main body 6 of the tractor 5 by the springs 7 and 8 co-axially mounted on the rod 9, which springs restrain the oscillation of the tractor with respect to the frame and, consequently, materially assist in steadyng the tractor 1 as it passes over the surface to be graded.

The frame 1, at its forward end, is supported by steering wheels 10 which are mounted upon the axle carried by the framework 11 rigidly secured to the front end of the frame 1. The wheels 10 are steered by means of the steering shaft 12, which has terminally mounted thereon a steering wheel 13. Depending from the frame 1 forwardly of the tractor 5 and rearwardly of the steering wheels 10 is an operator's platform 14 from which position the operator has easy access to the devices for manipulating the various parts of the machine. The frame 11 has rearwardly projecting arms 15 and 16 which are adapted to receive a pin 17 to which is pivotally secured the auxiliary implement-carrying frame 18 which extends rearwardly of the wheels 10 and which is vertically adjustably supported by the members 19 which are controlled by the wheels 20 mounted on the frame 1 adjacent the operator's platform 14.

The annexed drawings and the following

The auxiliary implement-carrying frame 18 is comprised of a pair of converging members 21 and 22, which are united at their forward ends by the plate 23 which has an 5 aperture 24 formed centrally thereof to receive the pin 17. The members 21 and 22 are united at their other ends by means of the member 25 to which is secured the cross member 26. The cross member 26 has its 10 terminal portions 27 adapted to receive the lower end 28 of the adjusting arms 19 by which the frame 18 is raised, lowered, or otherwise adjusted.

Depending from the cross member 26 is a 15 pair of brackets 29 which are pivotally secured to the cross member 26 by means of the pins 30 engaging the depending portions of connecting members 31. Intermediately of the brackets 29 are members 32 and 33 which 20 are mounted at their upper ends 34 and 35, respectively, between the depending portions of the connecting members 36 and 37 which are centrally secured to the cross member 26 and the plate 25. To the forward end 25 of the auxiliary implement-carrying frame 18 is connected depending supporting member 38 which has apertures 39 formed therein in spaced vertical relation.

Rigidly secured to the members 32 and 33 30 are the forwardly extending members 40 which have aligned apertures formed therein adapted to receive the pin 41 which is adjustably positioned in one of the apertures 39 in the member 38. Rearwardly of the forward end of the members 40 and positioned therebetween is the terminal portion of a plow beam 42 which is secured thereto by means of the pin 43. The plow beam 42 extends rearwardly and downwardly and 35 passes intermediately of the members 40 which members are secured to the brackets 29, and the entire assemblage is united by means of the pins or bolts 44. To the downwardly extending portion 45 of the plow beam is secured the grading implement which is in the form of a scraper blade 46 which has a cutting blade 47 extending longitudinally thereof at its lower edge and which is secured thereto by means of the bolts 48. The terminal portion 49 of the scraper blade 46 is formed into a moldboard 49' which has a 40 longitudinally extending and diagonally disposed plowshare 50 attached to its lower edge and a landside 51 connected thereto on the opposite side from the share 50.

The members 40 carry discs 52 and 53 which are revolvably mounted on shafts 54 and 55, respectively, which shafts are supported by the members 56 and 57 which are 45 secured to the member 40 by means of the plates 58 and 59 and the bolts 60. The lower edge of the forward disc 53 is disposed above the lower edge of the disc 52 in order to facilitate breaking of the ground in advance of 50 the plow.

It will be seen that, in the employment of the mechanism just described, the solid shoulder which occurs adjacent the body of asphalt or macadam comprising the main portion of the road, may be quickly and easily 70 cut away, and the material so cut away evenly distributed to provide a bed for the concrete shoulder to be formed in place of the soft shoulder just removed. When the mechanism comprising my invention is employed, 75 the plow carried by the end of the grader blade effects a substantially square cut adjacent the body of asphalt or macadam and this material which is so cut up is then evenly distributed laterally and no further operation 80 is necessary to place the shoulder in shape to receive concrete.

Further advantages in the mechanism will be apparent to those acquainted with the art, and its general utility over the types of construction now in common use can readily be appreciated.

Other modes of applying the principle of my invention may be employed instead of the one explained, change being made as regards 90 the mechanism herein disclosed, provided the means stated by any of the following claims or the equivalent of such stated means be employed.

I therefore particularly point out and distinctly claim as my invention:—

1. In a road grader, the combination of a frame; a plow and supporting means therefor; a moldboard for said plow, said moldboard formed as a scraper blade; and a plurality of discs longitudinally disposed in front of said plow, said discs adapted to successively cut the earth in front of said plow to different depths.

2. In a road grader, the combination of an 100 implement-carrying frame; driving means supporting one end of said frame; steering means supporting the other end of said frame; an auxiliary frame pivotally and vertically adjustably supported by said implement-carrying frame intermediately of said driving and supporting means; a plow beam supported on said auxiliary frame; a plow supported by said plow beam; and a moldboard for said plow formed as a scraper blade 110 extending laterally therefrom, and a plurality of discs carried by vertical elements secured to said auxiliary frame and longitudinally disposed in front of said plow, said discs adapted to successively cut the earth in front of said plow to different depths.

3. In a road grader, the combination of an 120 implement-carrying frame, rearwardly disposed driving means and forwardly disposed steering means, intermediate of said driving and steering means, a removably secured auxiliary frame adapted to be vertically adjustably supported and to carry a plow share and mold board, and a plurality of longitudinally disposed discs in front of said plow.

4. In a road grader, the combination of an implement-carrying frame, rearwardly disposed driving means and forwardly disposed steering means, a removably secured triangular auxiliary frame, said frame being forwardly pivotally supported at two points by means of vertically adjustable depending members, said auxiliary frame being adapted to carry a single plow beam and a plurality of longitudinally disposed discs in substantially the same plane as said plow beam, said disc being adapted to successively cut the earth in front of said plow to different depths.

Signed by me this 6th day of Nov., 1929.

15 GEORGE D. SHAEFFER.
